(57) CLAIM

The ornamental design for a planter block, shown and described.

DESCRIPTION

FIG. 1 is a perspective view of a planter block;
FIG. 2 is a front elevation view thereof, which is a mirror image of the rear elevation view;
FIG. 3 is a left side elevation view thereof, which is a mirror image of the right side elevation view;
FIG. 4 is a top plan view thereof; and,
FIG. 5 is a bottom plan view thereof.
The broken lines represent portions of the design that form no part of the claim.

1 Claim, 5 Drawing Sheets
